UNITED STATES PATENT OFFICE

IMOGENE DE LANCY, OF NEW YORK, N. Y., ASSIGNOR TO OTIS COMPANY, INC., OF BOSTON, MASSACHUSETTS, A CORPORATION OF MASSACHUSETTS

DESIGN FOR A TEXTILE FABRIC

Application filed February 7, 1929. Serial No. 29,969. Term of patent 3½ years.

To all whom it may concern:

Be it known that I, IMOGENE DE LANCY, a citizen of the United States, residing in New York, in the county of New York, State of New York, have invented a new, original, and ornamental Design for a Textile Fabric, of which the following is a specification, reference being had to the accompanying drawing, forming part thereof.

A single unit of my design is substantially comprised within the area defined by the indicating lines shown on the drawing.

The figure is a plan view of a textile fabric showing my new design.

I claim:

The ornamental design for a textile fabric substantially as shown and described.

IMOGENE DE LANCY.
